UNITED STATES PATENT OFFICE.

ARTHUR J. WILKIN, OF LOS ANGELES, CALIFORNIA.

DRIP CUP.

Application filed November 11, 1920. Serial No. 423,299.

To all whom it may concern:

Be it known that I, ARTHUR J. WILKIN, a citizen of the United States, residing at Los Angeles, in the county of Los Angeles and State of California, have invented new and useful Improvements in Drip Cups, of which the following is a specification.

This invention relates generally to faucets, and more particularly to an attachment in the nature of a cup or receptacle that is mounted for swinging movement upon the discharge spout or nozzle of a faucet, and which is for the purpose of receiving and retaining any drip that may discharge from the faucet after the latter has been closed to cut off the flow of liquid therethrough.

The principal object of the invention is to provide a relatively simple drip-catching attachment for faucets, that is capable of being easily and cheaply produced, and which may be readily applied to, or removed from the discharge spout or nozzle of the faucet.

A further object of the invention is to provide simple means for pivotally mounting the device upon the faucet so that it may be readily swung into an "out of the way" position when the faucet is opened to permit the discharge of liquid, and which device when released will by gravity, immediately return to its normal or drip-catching position.

Drip catchers of my improved construction are particularly intended for use on the faucets of oil or liquid hydrocarbon containers, and by the use of the device, the drippings of oil or similar liquids from the faucets are caught and prevented from dropping onto the floor and spreading thereupon, and which latter action, it will be understood, materially increases fire hazards.

With the foregoing and other objects in view, my invention consists in certain novel features of construction and arrangement of parts, that will be hereinafter more fully described and claimed, and illustrated in the accompanying drawings, in which:

Figure 1 is a perspective view of a faucet and showing one of the drip-catching devices applied to the nozzle or discharge spout thereof.

Fig. 2 is an enlarged detail section taken approximately on the line 2-2 of Figure 1.

Fig. 3 is an enlarged vertical section taken approximately on the line 3-3 of Fig. 2.

Referring by numerals to the accompanying drawings, which illustrate the practical embodiment of the invention, 10 designates a faucet of ordinary construction that is provided with a downwardly curved spout or nozzle 11, and formed in the side faces of the latter near the lower or discharge end, are relatively shallow recesses or indentations 12, the same serving as bearing seats 60 for the trunnions of my improved drip-catcher.

While these recesses or indentations may be formed in any suitable manner and of any desired shape, a simple and convenient 70 method of forming them is by the use of a center punch and hammer.

The drip cup contemplated by the invention is in the form of a small substantially cylindrical receptacle and comprises an annular wall 13 and bottom plate 14, the same being preferably formed from a single piece 75 of suitable sheet metal.

Projecting upwardly from the wall 10 is a pair of oppositely arranged ears 15, that are indented or pressed inwardly, to form 80 relatively small inwardly projecting trunnions 16, the same being substantially conical in shape, and when the device is applied to the nozzle of the faucet these trunnions 85 engage in the recesses 12.

The degree of frictional bearing of the trunnions 16 against the bearings 12, is such that the body of the cup or receptacle will readily swing forwardly or rearwardly from 90 its normal position directly below the discharge end of the spout or nozzle.

When the faucet is opened to permit the flow of liquid therethrough, the drip cup or receptacle is engaged by the container 95 that is to receive the discharged liquid and swung either forwardly or rearwardly into an "out of the way" position, as illustrated by dotted lines in Fig. 2, and when so positioned the liquid is free to discharge from 100 the end of the spout or nozzle of the faucet into the container. When the drip cup is swung upwardly into an "out of the way" position, and said cup passes above a horizontal plane, any liquid remaining in the 105 cup will automatically discharge into the liquid receptacle positioned beneath the faucet.

Immediately after the faucet is closed to cut off the flow of liquid therethrough, the 110 drip cup is permitted to swing by gravity to its normal position, and any liquid that

may flow downwardly through the spout or nozzle of the faucet, after the valve therein has been closed, will discharge or drip into the cup or receptacle and be retained therein, thereby preventing the drip from passing onto the floor immediately below the faucet.

While the improved drip-catcher may be advantageously utilized upon all liquid container faucets, it is particularly designed for use upon the faucets that control the discharge of oils, liquid hydrocarbons and like inflammable fluids from their containers, and it will be readily understood that by the use of drip catchers on these faucets the liability of fires is minimized, owing to the absence of drip and spread of oils and the like upon the floors immediately below and adjacent to the faucets.

Further, the use of the drip cup is instrumental in effecting the saving of considerable quantities of oil, or like fluids, and which would otherwise be wasted or rendered unfit for use after being recovered.

In many automobile service stations the faucets of the oil and liquid hydrocarbon containers are opened hundreds of times a day, and the use of the improved drip cup on such faucets will consequently effect a material saving of lubricating oils, gasoline, and the like.

Further, the use of the drip cup will be effective in a material saving of time, for the operator after closing, the faucet to which the cup is attached is not required to hold the container beneath the faucet until the "drip" of the liquid has ceased.

The simple method of attaching the device to any style, or size of faucet and which consists of two light blows of a hammer upon an ordinary center punch, constitutes a material element of economy and adaptability.

The drip-catching cup of my improved construction is very simple, may be easily and cheaply produced, is capable of being easily and quickly applied to, or removed

from operative position upon the faucet, and the cup or retainer maintains its operative position through gravity, and is effective in catching and retaining all drippings from the faucet which might otherwise discharge onto the floor.

It will be readily understood that minor changes in the size, form and construction of various parts of my improved device may be made and substituted for those herein shown and described, without departing from the spirit of my invention, the scope of which is set forth in the appended claims.

I claim as my invention:

1. A drip-receiving cup for faucets comprising a receptacle, oppositely disposed ears projecting upwardly from said receptacle, and portions of said ears being pressed inwardly to form trunnions that are adapted to engage the discharge end of a faucet nozzle.

2. The combination with a faucet provided on the lower portions of its nozzle with oppositely disposed indentations, of a drip-receiving cup positioned below the discharge end of said nozzle, oppositely disposed ears projecting upwardly from said drip cup and portions of which ears are pressed inwardly to form trunnions that are journaled in the indentations in the nozzle of said faucet.

3. The combination with a faucet provided with oppositely disposed bearings on its nozzle, of a drip receiving member normally positioned below the discharge end of the nozzle of said faucet, and having integral parts that are journaled in the bearings on said nozzle.

4. A drip cup for faucets comprising a receptacle, ears projecting upwardly from the receptacle and formed integral therewith, and integrally formed trunnions projecting inwardly from said ears.

In testimony whereof I have signed my name to this specification.

ARTHUR J. WILKIN.
